R. A. LIGHT ET AL

OIL CUP

Filed Sept. 25, 1923

UNITED STATES PATENT OFFICE.

RALPH A. LIGHT AND JOSEPH W. PRICE, JR., OF PHILADELPHIA, PENNSYLVANIA, ASSIGNEES TO THE UNITED STATES METALLIC PACKING COMPANY, OF PHILADELPHIA, PENNSYLVANIA, A CORPORATION OF PENNSYLVANIA.

OIL CUP.

Application filed September 25, 1923. Serial No. 664,678.

Our invention relates to the construction of oil cups and particularly to the type of cups in which the cup proper is cast around a perforated shank, preferably of steel, by means of which shank it is attached to a machine and through which shank it delivers oil to the part to be lubricated. The object of our invention is to generally improve the construction of cups of this kind particularly with respect to the construction and mode of attachment to the cover of the oil cup and with regard to the combination of the shank with the cast portion of the cup. The nature of our improvements will be best understood as described in connection with the drawings which illustrate an oil cup embodying our improvements and in which

Figure 1 is a top view of the oil cup with the wings of the cover in position to cover the filling openings.

Figure 2 is a cross section on the line 2—2 of Fig. 1.

Figure 3 is a view of the bottom of the oil cup.

Figure 4 is a side elevation of the oil cup shown partly in section on the line 4—4 of Fig. 1.

Figure 5 is a view similar to Fig. 1 but showing the cover rotated to the position in which the filling openings are accessible, and

Figure 6 is a sectional view taken through a portion of the lead, taken on the line 6—6 of Fig. 1.

A is the shank of the oil cup preferably made of steel and externally threaded at its lower end which projects below the cup. This shank is longitudinally perforated, the perforation including an internally threaded portion B at the top of the shank, an intermediate portion B' of smaller diameter having a valve seat B² at its top and merging into the portion indicated at B³. The shank is transversely perforated, as indicated at C, immediately above the valve seat B². D indicates a lateral projecting flange of angular outline formed on the portion of the shank to which the cup proper is cast, and E indicates a similar projecting flange formed lower down on the shank and having a face E' which projects below the cast cup and is adapted to rest upon a portion of the machine into which the threaded portion of the shank screws. F is the cast portion of

the cup, the bottom portion F' of which is cast around the flange D and around the outer portion of the flange E, as shown. The lower portion of the cup casting is preferably given a hex form, as indicated at F², so that it can be conveniently engaged by a wrench. F³ indicates the inwardly projecting top of the cast cup. This is formed with filling openings F⁴ on opposite sides and with a centrally located seat opening indicated at F⁵. The seat opening and the filling openings are surrounded by upwardly extending rims or flanges, indicated at F⁶, the upper surfaces of which lie in the surface of a cone. G indicates the cover for the oil cup which is formed with two projecting arms G' extending from a central depressed boss G² which fits in the seat F⁶ and is formed with an inwardly projecting flange G³ which serves as the seat for a spring. The wings or arms G' of the cover which slope downward to fit on the rims surrounding the filling holes are formed with depressions G⁴ which taper to a shoulder G⁵ and they are also formed with upwardly extending lugs G⁶. H is a spindle carrying a valve H³ at its lower end and threaded, as indicated at H', to screw into the threaded perforation D. At the top of the spindle is formed an outwardly extending flange H⁴ and an upwardly extending portion, indicated at H⁵. I indicates a spring seated on the top of the spindle B and abutting against a shoulder and the upper portion of the spindle H. I' is a spring seated on the shoulder G³ of the cover and abutting against the flange H⁴ of the spindle. The function of this spring is to press the cover downward on to the top of the cup.

When it is desired to fill the cup with oil the cover is turned to the position shown in Fig. 5, the tapered depression G⁴ riding readily over the edges of the filling openings. A rotation of the cover in the opposite direction is prevented by the engagement of the shoulder G⁵ with the edges of the rim F⁶ surrounding the filling openings so that the cover can only be rotated in one direction, and this is important as it protects the cover from being rotated in a direction which would tend to unscrew the valve spindle and change the adjustment of the valve. The sloping form of the cover

prevents the accumulation of water over the cup.

Having now described our invention, what we claim as new and desire to secure by 5 Letters Patent, is:

1. A cast metal oil cup having a perforated steel shank about which this cup is cast and which extends below the cup and upward into the cup, said shank having a 10 thread formed at the top of the perforation for a valve spindle, said cup having a top on which the cover fits and which is formed with a downwardly centrally located bearing for a cylindrical boss of the cover and 15 with filling openings lying outside of said bearing, in combination with a rotatable cover having a depressed cup shaped boss extending down into the centrally located bearing in the top and adapted to form a 20 seat and container for a coiled spring, said
- cover having laterally extending wings adapted to cover and uncover the filling openings in the top of the cup as the cover is rotated, means for preventing the rotation of the cover in a backward direction, a 25 valve stem extending through the boss of the cover and screwing into the threaded perforation of the steel shank, said stem having a flange at its top, and a spring seated in the cup shaped boss of the cover 30 and abutted against the flange of the valve stem.
2. An oil cup having the features of claim 1 and further characterized by having its steel shank formed with a laterally extend- 35 ing seat portion extending below the cast cup portion of the structure.
